STANLEY DE WAAL, OF SAN ANTONIO, TEXAS, ASSIGNOR TO FRIGIDAIRE CORPORATION,
OF DAYTON, OHIO, A CORPORATION OF DELAWARE

REFRIGERATING APPARATUS

Application filed May 28, 1930. Serial No. 456,616.

This invention relates to evaporators for refrigerating apparatus and more particularly to the refrigerant control mechanism for such evaporators.

5 One of the objects of this invention is to provide an improved refrigerant control mechanism for an evaporator for a refrigerating apparatus, which control mechanism includes a valve, and to arrange said mechanism in such a manner so as to prevent damage to said valve or its seat in the event said evaporator is subjected to abnormal conditions.

10 More specifically it is an object to prevent 15 the aforesaid valve from jamming its seat during transportation of said evaporator.

Further objects and advantages of the 20 present invention will be apparent from the following description, reference being had to the accompanying drawings, wherein a preferred form of the present invention is clearly shown.

In the drawings:

25 Fig. 1 is a view illustrating diagrammatically a refrigerating system including the evaporator, on a larger scale, embodying features of the present invention, said evaporator being shown in cross section, and

30 Fig. 2 is a fragmentary view of a portion 35 of the evaporator shown in Fig. 1, the view being taken in the direction of the arrows 2-2.

Referring to the drawings, the numeral 20 designates in general an evaporator, comprising a header or container 21 forming a reservoir for liquid refrigerant, such as sulphur dioxide, and from which header depends a plurality of refrigerant conveying ducts 22 for conveying the refrigerant to the 40 zone or place to be refrigerated. Refrigerant is delivered to the header through refrigerant conveying pipe 24 and is withdrawn through a vapor pipe 25. The pipe 24 is connected with a receiver 27 and the pipe 25 is connected to the low pressure side of a compressor 30, preferably as shown to the crank case thereof. The high pressure side of the compressor is connected with a condenser 31 which in turn is connected with the receiver 27. The compressor is herein

shown as driven by a motor 33 which is controlled in response to the pressure within the pipe 25 by means of an automatic switch 34 which connects the motor with the power mains 35.

55 The header 21 which is herein shown as a refrigerant containing chamber is formed of a drawn sheet metal tube having one end thereof open which receives a ring 40 which is suitably sealed in position. A head or valve plate 42 is secured to the ring 40 by screws 43 and carries shut off valves 44 and 45 which are connected respectively with pipes 24 and 25. The head 42 is provided with an opening 47 communicating with the 60 valve 45 and carries an inwardly extending and upwardly sloping tube 48 for conveying gaseous refrigerant from the free space above the liquid in the refrigerating chamber. The head 37 is also provided with a cylindrically 65 shaped inwardly extending boss 50 having a screened opening 51 which communicates with the valve 44. The size of the opening 51 is reduced to a small orifice 53 which provides a seat for a needle valve 55. A sleeve 70 75 80 85 90 95 100 58 is secured to the boss 50 and is provided with an inwardly extending ledge or support 60 for supporting a float lever 61 and float 62. The float lever is of the bell crank type, one end thereof carrying the float 62 and the other end being operatively connected with the needle valve 55 by a pivotal connection 63. The support 60 is bifurcated at 65 to receive a portion of the float lever 61. The float lever 61 is pivotally mounted between the forks of the support 60 by means of a pin 67 carried by the lever 61, which pin extends through aligned slots 68 provided in the forks of said support. The aligned slots 68 provide a fulcrum for the float lever 61.

It will be apparent from the foregoing that the flow of refrigerant through the evaporator will be controlled by the needle valve 55 which controls the flow of refrigerant from the receiver 31 and this flow is responsive to the float 62 so that when a predetermined quantity of refrigerant is contained within the chamber 21, the float will close or tend to close the needle valve and thus stop or impede the flow of refrigerant

to the evaporator. For the purpose of illustration I have shown the refrigerant level at 80 and an oil level at 81.

When the pin 67 is in the position shown in the drawings, the float 62 will be in its normal operating position to actuate the valve 55. Means may be provided for yieldably maintaining said float in normal operating position, which means may comprise a

- 10 pair of springs 70. The springs 70 are secured on the one end thereof to pins 71 carried by the support 60 and the opposite ends of said springs being secured to the pin 67 carried by the float lever 62. The springs 15 70 are adapted to maintain the pin 67 in engagement with the left end of the slots 68, as viewed in the drawings, during normal operation of the float. Thus, when the pin is in the position shown, the float lever 61 will be 20 maintained in its normal operating position.

In the event the mechanism including the float is subjected to abnormal conditions, such as severe shocks, such as may occur during transportation of the evaporator, the float 25 62 would be jarred upwardly very quickly and if it were not for the yieldable mounting of said float lever, said float would jam the needle valve 55 into its seat and thereby damage said valve or its seat. Thus, when this 30 abnormal condition occurs, the springs 70

will yield and permit the pin 67 to slide to the right in the slots 68, as viewed in the drawings, to thus prevent said float mechanism from jamming the needle valve into its 35 seat by avoiding the direct thrust of the float lever upon the valve 55. After the shocking or jarring of the float is over, the springs 70 will return the pin 67 to the position shown in the drawings.

- 40 40. In order to prevent the valve 55 from being removed too far from its seat, the float lever 61 is provided with a stop 75 which engages the support 60 when the float lever 61 reaches a predetermined position.

- 45 45. While the form of embodiment of the invention as herein disclosed constitutes a preferred form, it is to be understood that other forms might be adopted, all coming within the scope of the claims which follow.

50 What is claimed is as follows:

1. In an evaporator for refrigerating apparatus, the combination with a valve, of a float for actuating said valve, and means for yieldably maintaining said float in normal operating position.

- 55 2. In an evaporator for refrigerating apparatus, the combination with a valve, of a float for actuating said valve, a support for said float, and means for yieldably maintaining said float in a predetermined position with respect to said support.

- 60 65 3. In an evaporator for refrigerating apparatus, the combination with a valve, of a float for actuating said valve, a support for said float, and resilient means for normally

maintaining said float in a predetermined position with respect to said support.

4. In an evaporator for a refrigerating apparatus, the combination with a valve, of a float for actuating said valve, said float being pivotally connected with the valve, and resilient means for normally maintaining said pivotal connection in a predetermined position.

5. In an evaporator for a refrigerating apparatus, the combination with a valve, a float, a float stem having a pivotal connection with said valve, a support for said float and stem, said support serving as a fulcrum for said float and stem, and resilient means normally 80 maintaining a predetermined fulcrum point for said float and stem.

6. In an evaporator for a refrigerating apparatus, the combination with means forming a reservoir for liquid refrigerant, of 85 means forming a restricted passageway, a valve for controlling said passageway, a float for controlling said valve, a bifurcated support for said float and having aligned slots serving as a fulcrum for said float, and a 90 plurality of springs for normally maintaining a predetermined fulcrum point within said slots.

In testimony whereof I hereto affix my signature.

STANLEY DE WAAL.
